UNITED STATES PATENT OFFICE.

WILLIAM G. SCHNEIDER, OF NEW YORK, N. Y., ASSIGNOR TO WILBUR A. COCHRANE, OF SEA CLIFF, LONG ISLAND, NEW YORK.

LAMP-HOLDER.

1,212,406.

Specification of Letters Patent. Patented Jan. 16, 1917.

Application filed January 2, 1914. Serial No. 810,693.

To all whom it may concern:

Be it known that I, WILLIAM G. SCHNEIDER, a citizen of the United States, residing at New York city, county of Queens, and State 5 of New York, have invented certain new and useful Improvements in Lamp - Holders, fully described and represented in the following specification and the accompanying drawings, forming a part of the same.

10 This invention relates to an improved lamp holder intended to be inserted in a timber, bank of dirt, or other surface, to temporarily support the lamp, the holder being particularly intended for use with small 15 lamps, such as miners' lamps which are ordinarily carried by being attached to the clothing or cap of the miner.

The object of the invention is to provide a simple, cheap and strong lamp holder so 20 constructed that the lamp may be readily and conveniently inserted and removed therefrom.

With this and other objects not specifically referred to in view, the invention consists 25 in a certain construction hereinafter described and fully pointed out.

Referring to the accompanying drawings, Figure 1 is a perspective view of a lamp holder constructed in accordance with the invention with a lamp in place therein. Fig. 30 2 is a plan view of the lamp holder.

Lamp holders constructed in accordance with the invention will consist of a single 35 piece of spring wire, this wire being bent to form a bow handle comprising two members, marked 1 and 2 in the drawings. In the best constructions embodying the invention, the members will be crossed, as shown in Fig. 2. As illustrated, the member 2 is further bent to provide a socket, as 3, and a supporting prong, as 4, the junction between the socket and the prong being indicated at 5. In the best constructions embodying the invention, this junction or shoulder will be 40 rounded, as indicated. The prong is provided with a sharpened end, indicated at 6, this end being of such angular shape as to prevent the support from turning under the weight of the lamp when the point is stuck 45 into a timber or ore bank. The member 1 is provided with a bearing end, indicated at 7, which, in the best constructions embodying

the invention, will be rounded as shown. This end is located at a sufficient distance from the junction or shoulder 5 to form a 55 throat which is less in extent than the diameter of the lamp with which the support is to be used. When the lamp is inserted in the holder, therefore, it is forced through the throat, the rounded end 7 and the rounded 60 shoulder or junction piece facilitating the movement of the lamp into the support.

With this construction the lamp holder may be made of strong and comparatively heavy and stiff wire, and yet the lamp can be 65 inserted without undue effort on the part of the operator, because the lamp itself serves to spring back the bearing member as it moves into and out of position. It is unnecessary, therefore, to use any great amount of 70 force in springing the bearing end back to permit the lamp to pass into the holder, as the lamp itself largely, if not entirely, effects the backward movement of the bearing end which permits the lamp to slip into the 75 holder. It will be observed that the support is exceedingly simple and, therefore, cheap in construction, and that the bow not only serves as a handle but enables the support to be hung up on any convenient projection. 80

What is claimed is:

1. A lamp holder consisting of a single piece of spring wire bent to form a bow projecting beyond the lamp when in position and dimensioned to provide a handle by 85 which the holder and lamp may be carried, said bow comprising a pair of spring members one of which is formed to provide a part of a lamp socket and a supporting prong, and the other of which completes the 90 socket and has a rounded bearing end located at a sufficient distance from the junction between the socket and the prong to form a throat through which the lamp may be forced into the socket against the tension 95 of the bearing end and held therein by the spring of the members.

2. A lamp holder comprising a single piece of spring wire bent to form a bow handle comprising a pair of crossed spring 100 members, one member being formed to provide a lamp socket and a supporting prong, the junction between the two being rounded, and the other member forming a part of the

socket and having a rounded bearing end which is located at a sufficient distance from the junction between the socket and the prong to form a throat through which the lamp may be forced into the socket against the tension of the bearing end.

5 In testimony whereof, I have hereunto set

my hand, in the presence of two subscribing witnesses.

WILLIAM G. SCHNEIDER.
